UNITED STATES PATENT OFFICE.

EDMUND SPENSER TIDDEMAN, OF HORNCURCH, ENGLAND, ASSIGNOR TO W. R. SYKES INTERLOCKING SIGNAL COMPANY LIMITED, OF CLAPHAM, LONDON, ENGLAND.

RAILWAY SIGNALING APPARATUS.

Application filed July 24, 1920. Serial No. 398,786.

(GRANTED UNDER THE PROVISIONS OF THE ACT OF MARCH 3, 1921, 41 STAT. L., 1313.)

To all whom it may concern:

Be it known that I, EDMUND SPENSER TIDDEMAN, of Wood End, Great Nelmes, Hornchurch, in the county of Essex, England, a subject of the King of Great Britain, have invented certain new and useful Improvements in and Relating to Railway Signaling Apparatus (for which I have filed an application in England, May 1st, 1915, 10 Patent No. 6499), of which the following is a specification.

This invention relates to that class of apparatus destined on the one hand to apply the brakes of a train or railway vehicle and give a corresponding danger signal in both cases by mechanical means and on the other hand to restrain the application of the brakes and indication of the danger signal by electrical means adapted to substitute a 20 safety signal indication for that of the danger signal, the said electrical means embodying a polarized relay for the purpose of discriminating between safety signals on single line systems.

Now the object of the present invention is to effect a simplification by arranging that the danger signal indication shall follow as the result of applying the brakes, the rush of air in the train pipe system due to such 30 application sounding a whistle or syren.

The invention further consists in the construction and arrangement of parts herein-after described with reference to the accompanying drawings whereof Fig. 1 is a diagram of the general arrangement. Figs. 2 and 3 are elevations at right angles one to the other and Fig. 4 is a plan of a portion of the apparatus employed, parts being in section.

As here shewn, *a* and *b* are two parts of a plunger adjustably connected together and working in a guide *c* carried by the locomotive for example. *d* is an insulated track ramp adapted to be connected to one pole of an earthed battery *e* by a switch *f* only when the signal is at line clear and *f*¹ is an insulated shoe upon the plunger part *a* adapted to co-operate with the ramp *d* which latter forces the plunger *a* *b* upwards against the 50 pressure of a spring *g*. The train pipe of the brake system is connected to a valve body *h* at *i*, the arrangement being such that when the valve *j* in the body *h* is allowed to open,

air, on the assumption that a pressure brake system is being dealt with, will escape 55 through a pipe *k* and blow a whistle *m*. The valve *j* is normally held closed by a lever *n* under the conjoint control of a trigger *o* carried by the plunger part *b* and of a magnet lever *p* shown as coupled to the valve lever 60 *n* by a toggle link *r*.

The arrangement is such that every time the plunger *a* *b* encounters a ramp *d* whether it be electrically alive or dead, the valve lever *n* is released by the trigger *o*, but unless the ramp be dead the said valve lever *n* is prevented from moving to open the brake valve by reason of the restraint exerted by the magnet controlled linkage system *p* *r*. The energizing of the magnet, which is indicated 70 at *s*, occurs when the ramp *d* encountered is alive irrespective of its polarity, the magnet circuit being earthed at *t*, as is also the circuit of a polarized relay *u* which, unlike the magnet *s*, discriminates between ramps of 75 opposite polarity, and can thus be made to selectively complete the circuit *v* of a "signal clear" bell *w*.

The trigger *o* normally engages a stop *x* on the plunger part *b* under a yielding load 80 such as that of a spring *y*, the arrangement being such that after the valve lever *n* has been released by the trigger *o* and moved to open the brake valve and blow the whistle, the trigger with descent of the plunger will 85 remain behind through engagement with the projection *n*¹ on the lever *n* until the latter is reset when it is returned by the reaction of the spring *y* to again engage its stop *x*.

The resetting of the valve lever *r* is effected by a link *z* connected by a bell crank 1 to the piston of an air motor 2 to which fluid can be supplied by piping 3 from a suitable reservoir under the control of a button valve 4 upon the vehicle. 90

Having now particularly described and ascertained the nature of my said invention and in what manner the same is to be performed, I declare that what I claim is:

1. In railway signal apparatus, the combination of an air brake system, a whistle connected therewith, a brake valve in said system controlling the connection with said whistle, a lever for maintaining said valve in its closed position, a slideable plunger, and 105 a trigger carried by said plunger and ar-

ranged to lock and unlock the brake valve lever in accordance with the movements of said plunger.

2. In railway signal apparatus, the combination of an air brake system, a whistle connected therewith, a brake valve in said system controlling the connection with said whistle, a lever for maintaining said valve in its closed position, a slidable plunger, a trigger carried by said plunger and arranged to lock and unlock said brake valve lever in accordance with the movements of said plunger, an electro-magnet and a linkage system connected with said brake valve lever and controlled by said electro-magnet to lock said brake valve lever in its operative position or to permit it to move to an inoperative position whereby the brake valve is opened and the whistle sounded.

3. In railway signal apparatus, the combination of an air brake system, a whistle connected therewith, a brake valve in said system controlling the connection with said whistle, a lever for maintaining said valve in its closed position, a slidable plunger, a trigger carried by said plunger and arranged to lock and unlock said brake valve lever in accordance with the movements of said plunger, an electro-magnet, a linkage system connected with said brake valve lever and controlled by said electro-magnet to lock said brake valve lever in its operative position or to permit it to move to an inoperative position whereby the brake valve is opened and the whistle sounded, and means for resetting said brake valve lever to its operative position.

4. In railway signal apparatus, the combination of an air brake system, a whistle connected therewith, a brake valve in said system controlling the connection with said whistle, a lever for maintaining said valve in its closed position, a slidable plunger, a trigger carried by said plunger and arranged to lock and unlock said brake valve lever in accordance with the movements of said plunger, an electro-magnet, a linkage system connected with said brake valve lever and controlled by said electro-magnet to lock said brake valve lever in its operative position or to permit it to move to an inoperative position whereby the brake valve is opened and the whistle sounded, and a pneumatically operated resetting motor connected with said linkage system for resetting said brake valve lever to its operative position.

5. In railway signal apparatus, the combination of an air brake system, a whistle connected therewith, a brake valve in said system controlling the connection with said whistle, a lever for maintaining said valve in its closed position, a slidable plunger,

a trigger carried by said plunger and arranged to lock and unlock the brake valve lever in accordance with the movements of said plunger, and a stationary ramp on the permanent way for operating said plunger. 65

6. In railway signal apparatus, the combination of an air brake system, a whistle connected therewith, a brake valve in said system controlling the connection with said whistle, a lever for maintaining said valve in its closed position, a slidable plunger, a trigger carried by said plunger and arranged to lock and unlock said brake valve lever in accordance with the movements of said plunger, an electro-magnet and a linkage system connected with said brake valve lever and controlled by said electro-magnet to lock said brake valve lever in its operative position or to permit it to move to an inoperative position whereby the brake valve is opened and the whistle sounded, a contact-shoe carried by said plunger, an electrically-conductive stationary ramp on the permanent way for contacting with said shoe and operating said plunger, a traffic-controlling signal adjacent the permanent way, an electric circuit and a switch therein closed when said signal indicates "line clear", said circuit, when such indication is given and the plunger-shoe contacts with the ramp, including the ramp, the contact-shoe, and said electro-magnet. 70 75 80 85 90 95

7. In railway signal apparatus, the combination of an air brake system, a whistle connected therewith, a brake valve in said system controlling the connection with said whistle, a lever for maintaining said valve in its closed position, a slidable plunger, a trigger carried by said plunger and arranged to lock and unlock said brake valve lever in accordance with the movements of said plunger, an electro-magnet and a linkage system connected with said brake valve lever and controlled by said electro-magnet to lock said brake valve lever in its operative position or to permit it to move to an inoperative position whereby the brake valve is opened and the whistle sounded, a contact-shoe carried by said plunger, an electrically-conductive stationary ramp on the permanent way for contacting with said shoe and operating said plunger, a traffic-controlling signal adjacent the permanent way, an electric circuit and a switch therein closed when said signal indicates "line clear", said circuit, when such indication is given and the plunger-shoe contacts with the ramp, including the ramp, the contact-shoe and said electro-magnet, and an electric bell on the train, controlled by the same circuit. 100 105 110 115 120
